UNITED STATES PATENT OFFICE.

WILLIAM LANYON AND ROBERT H. LANYON, OF PITTSBURG, KANSAS.

APPARATUS FOR CLEANING THE RESIDUUM FROM ZINC-RETORTS.

SPECIFICATION forming part of Letters Patent No. 319,270, dated June 2, 1885.

Application filed January 12, 1885. (No model.)

To all whom it may concern:

Be it known that we, WILLIAM LANYON and ROBERT H. LANYON, both citizens of the United States, and residents of Pittsburg, 5 Crawford county, Kansas, have invented certain Improvements in Apparatus for Cleaning the Residuum from Zinc-Retorts, of which the following is a specification.

Our invention consists of apparatus, fully 10 described and claimed hereinafter, for cleaning the residuum from zinc-retorts prior to recharging the same.

In the accompanying drawings, Figure 1 is 15 a front view of a bench of zinc-retorts with the suspended deflecting-shield in front of the same, and Fig. 2 an enlarged sectional perspective view illustrating our invention.

Referring in the first instance to Fig. 2, A is part of the brick-work or masonry in which 20 a series of retorts, B, are built, one only of these retorts being shown in this figure.

In front of the bench of retorts is a movable shield, D, more particularly referred to hereinafter, this shield having a number of openings, a.

A portable pipe, G, can be passed through 30 any one of the openings in the shield and into any one of the retorts. This pipe terminates at one end in a suitable nozzle, b, and being closed at its outer end, but communicating near the latter through a flexible pipe, H, with a steam-generator.

The attendant having introduced a portion 35 of the pipe into the retort lets on the steam by manipulating any appropriate valve with which the pipe may be furnished, and the consequence will be the injection of a forcible jet of steam into the retort. The steam will of course recoil, and the result will be the expulsion 40 from the mouth of the retort of the residuum which had been left in the same, this residuum striking the shield by which it is deflected onto the floor of the retort-house, or into a pit, w, made in the floor in front of the 45 bench of retorts.

The operator can so move the pipe about 50 that the steam may be directed to all parts of the retort. The shield protecting him from the flying residuum which is generally in a red-hot condition.

As particles of residuum might find their

way through the opening a in the shield and interfere with the comfort of the operator, we prefer to attach to the pipe a guard-plate, W, of sufficient size to deflect such particles as 55 may pass through the said opening in the shield.

In Fig. 1 we have shown the front of the bench of retorts, the latter being in the present instance in five horizontal rows, eleven retorts in each row, and the shield D being as long, or nearly so, as the bench, and having an opening, a, for each retort in a row.

The shield may be constructed and arranged in different ways in carrying out the invention. 65 In the present case it is suspended to two iron ropes or chains, h h, one near each end of the shield, and is suitably constructed so as to be easily raised and lowered, adjusted opposite to that row of retorts which has to be 70 operated on, and, finally, elevated out of the way when the whole of the retorts have been cleansed. This plan we prefer; but it is not necessary that the shield should be coextensive longitudinally with the bench of retorts, 75 or that it should be a suspended shield. It may, for instance, be more contracted in length and may be arranged to be moved on rollers over the floor of the retort-house; hence we do not desire to confine ourselves to a mov- 80 able shield of any specific construction.

We are aware that it has been proposed to construct a gas-retort discharging device consisting of a steam-pipe carrying a shield to 85 prevent the heated contents of the retort from striking the workman when he manipulates the pipe; but if the shield is made so large and heavy as to effect this result in our apparatus the pipe cannot be manipulated as it should be; hence we employ the main shield D supported independently of the pipe and perforated for the passage of the latter, the only shield carried by the pipe being the light disk W for shielding the workman from any particles which may pass through the perforation 95 of the main shield.

We therefore claim as our invention—

1. The combination of a bench of zinc-retorts, a portable pipe constructed for introduction into the retorts and communicating 100 through a flexible pipe with a steam-generator, and the shield D supported independently

of the pipe and perforated for the passage of
the latter, as set forth.

2. The combination of the pipe G, commu-
nicating with a generator and having a guard-
5 plate, W, with a bench of retorts, and a per-
forated shield, D, supported independently of
the pipe, as specified.

In testimony whereof we have signed our

names to this specification in the presence of
two subscribing witnesses.

WILLIAM LANYON.
ROBERT H. LANYON.
